FLUID COMPRESSOR

William H. Leinweber, Chicago, Ill.

Application February 2, 1945, Serial No. 575,747

2 Claims. (Cl. 230—172)

1

My invention relates to improvements in compressors and more particularly to a hollow piston closed at both ends having inlet outlet ports in the sides of the piston and a compression chamber therein to give greater vaporization of fluids.

The invention will be best understood by reference to the accompanying drawing forming a part of this specification, and in which,

Figure 1 shows a longitudinal, central sectional view of a device embodying my invention.

Figure 2 shows a similar view of the same illustrating the piston in a different position and disclosing the three compression chambers for its thruple compression.

Referring in detail to the form of my invention illustrated herewith, I have shown a compressor cylinder 14 containing a thruple piston 15 and having a head I provided with a discharge valve 6 and an inlet valve 8.

These valves and cylinder construction may be of any number or any type.

The bottom cylinder wall 16 has in its center a boss 10 in which piston rod 13 containing two piston rings 9 at the lower end is fitted into boss 10 similar as a piston is fitted into a cylinder and works in the same manner therein; this arrangement prevents leakage of fluid or the like from entering into the crank case and thinning out the oil.

The upper threaded end of the piston rod 13 is screwed into boss 12 in the hollow piston 15 this arrangement gives perfect alignment at all times a more even stroke of the piston and piston rod in boss 10 the efficiency is increased considerable for longer periods of time without repairs as no uneven wear to these parts occur at anytime.

The hollow piston 15 has inlet and outlet ports 11 at the sides of the piston which communicate through cylinder ports 7.

The operation of the compressor described is as follows:

Viewing the compressor with its parts in the position shown in Fig. 2, in which position the air or fluid from chamber 5 has been expelled into chamber 4 of the piston 15, the piston 15 is in substantially its lowermost position, with a wall thereof closing the port of the inlet valve 8, which inlet valve 8 is of a construction which admits air or fluid into the chamber 4 or 5 under certain conditions to be hereinafter noted. As the piston 15 moves upwardly, one of the ports of the lower ports 11 will register with the inlet valve 8 and a charge of air or fluid will be admitted to the chamber 4. As the piston moves up, this charge of air or fluid will be forced out of

2

the chamber 4 by the air or fluid compressed in the chamber 5 when the piston is in its lower position as shown in Fig. 2. This forced, compressed air or fluid from the chamber 4 will pass out through the upper ports 11 through the upper ports 7 into the chamber 3, from whence it passes out through the outlet valve 6 under compression. When the piston 15 is in its uppermost position, a position adjacent the top wall 12, the inlet valve 8 will communicate with the chamber 5 below the piston 15 and a charge of air or fluid will be admitted into the chamber from the inlet valve 8. As the piston moves downwardly, this charge of air or fluid from the chamber 5 will be forced through the ports 7 and 11 into the chamber 4 of the piston 15, and when the piston 15 reaches a point where one of the lower ports registers with the inlet valve 8, a charge of air or fluid will again be admitted to the chamber 4 of the piston. Thus, it will be apparent that the air or fluid compressed in chamber 5 being admitted through the ports 7 and 11 into the chamber 4, is met with a charge of air or fluid through the inlet valve 8, and this compressed air or fluid and the charge of air or fluid from the inlet valve 8 will then pass through the ports 11 and 7 into the chamber 3 where it will be re-compressed and expelled through the outlet valve 6. By this construction, it will be apparent that there are three stages of compression in the operation of the piston, the first stage being the compression of the air or fluid in chamber 5 and the expulsion of compressed air or fluid into chamber 4, where the compressed air or fluid is bombarded by a charge of air or fluid through the inlet valve 8. From this chamber 4, the compressed air or fluid is then admitted into the chamber 3 where it reaches the third stage of compression and is expelled through the outlet valve 6. As before stated, the valves 6 and 8 may be of any approved construction, it being the intention that as to the valve 8, air or fluid is admitted only into the chamber 5 and chamber 4 and escape of air or fluid is not permitted therefrom, whereas valve 6 is constructed to permit escape of air or fluid from chamber 3 but will not permit admission of air or fluid therein.

While I have illustrated and described the preferred form of construction for carrying my invention into effect, this is capable of variation and modification without departing from the spirit of the invention. I, therefore do not wish to be limited to the precise details of construction set forth, but desire to avail myself of such

variations and modification as come within the scope of the appended claims.

Having thus described my invention, what I claim as new and desire to protect by Letters Patent is:

1. A compressor comprising a body providing a piston chamber, a piston in said chamber and providing on opposite sides thereof, together with said body, compression chambers, said piston being of substantially hollow construction, means providing communication between the compression chamber on one side of the piston and the interior of said piston, means providing communication between the interior of said piston and the compression chamber on the other side of said piston, and means for charging a fluid to the interior of said piston chamber at a predetermined point in its movement within said cylinder.

2. A compressor comprising a body providing a piston chamber, a piston in said chamber and providing on opposite sides thereof, together with said body, compression chambers, said piston being of substantially hollow construction, means providing communication between the compression chamber on one side of the piston and the interior of said piston, means providing communication between the interior of said piston and the compression chamber on the other side of said piston, and means for charging a fluid to the interior of said piston chamber at a predetermined point in its movement within said cylinder, said last-named means including an inlet valve and ports formed in said piston for communication with said valve.

WILLIAM H. LEINWEBER.
